UNITED STATES PATENT OFFICE.

CHARLES WESLEY ROBISON, OF CRAFTON, PENNSYLVANIA.

RECEPTACLE.

1,228,824.

Specification of Letters Patent. Patented June 5, 1917.

Application filed December 13, 1916. Serial No. 136,589.

To all whom it may concern:

Be it known that I, CHARLES WESLEY ROBISON, a citizen of the United States of America, residing at Crafton, county of Allegheny, and State of Pennsylvania, have invented certain new and useful Improvements in Receptacles, of which the following is a specification.

This invention relates to match receptacles and has for its object to provide, in a manner as hereinafter set forth, a receptacle of such class, which is employed as a container in which the matches can be packed for shipping purposes, as the ordinary match box, but also as a match safe and container for the burnt match sticks.

A further object of the invention is to provide a match receptacle having means, in a manner as hereinafter set forth, whereby a match box can be quickly converted into a match safe so that the matches can be conveniently removed when desired.

Further objects of the invention are to provide a match receptacle for the purpose set forth which is simple in its construction and arrangement, strong, durable, efficient and convenient in its use, and comparatively inexpensive to manufacture.

With the foregoing and other objects in view the invention consists of the novel construction, combination and arrangement of parts, as hereinafter more specifically described and illustrated in the accompanying drawings, wherein is shown an embodiment of the invention, but it is to be understood that changes, variations and modifications can be resorted to which come within the scope of the claims hereunto appended.

In the drawings wherein like reference characters denote corresponding parts throughout the several views:—

Figure 1 is a perspective view illustrating the receptacle converted into a match safe and a container for burnt match sticks.

Fig. 2 is a vertical sectional view of the receptacle when set up as a match box for shipping and storage purposes.

Fig. 3 is a vertical sectional view, broken away, of the match safe.

Fig. 4 is a vertical sectional view of the inner section of the receptacle upon a reduced scale.

Referring to the drawings in detail the receptacle includes an outer and an inner section, the former comprises a bottom 1, a pair of side walls 2, 3, a back wall 4 and a front wall 5. The side and back walls are

of the same height or length. The front wall is of less height or length than the back wall. The front wall extends from the upper end of the side walls and terminates at a point removed from the bottom thereby providing the front of the outer section with a rectangular opening 6 for a purpose to be hereinafter referred to. The back wall at its upper end is formed with an opening 7.

The inner section, which contains the matches 22, is of less length than the outer section and when positioned within said outer section is mounted against the bottom thereof. The inner section is in the form of a tray and consists of a top 8, bottom 9, a pair of side walls 10 and a back wall. The upper portion of each side wall 10 is reinforced as at 12, and the lower portion of each side wall is also reinforced as at 13. The reinforcements are arranged on the outer faces of said walls and also provide means for causing a snug fit between the outer and inner sections when the latter is mounted in the former. The reinforcements 12, 13, are spaced from each other providing a pair of pockets 14, for a purpose to be referred to.

Forming a part of the bottom 9, at the front thereof as well as being hinged therewith, is a trough forming member consisting of a rectangular front piece 15 having a pair of inward extensions 16, of triangular shape, which have their inner ends provided with protuberances 17, providing stops and each of which has a metallic reinforcement 18 for stiffening purposes. The trough forming member when the receptacle is not used as a match safe is arranged whereby the front piece 15 will extend across the inner section, bearing against the side walls thereof, and the triangular extensions will be positioned in the pockets 14. The tray forming member is maintained in the position stated by a severable strip 20 which is secured to the outer face of the lower portion of the front wall 5 and the upper portion of the outer face of the front piece 15.

The strip 20 is termed a holding member and has a suitable inscription, as at 21, to indicate where the strip is to be cut, so as to free the trough forming member, to enable the latter to swing forward through the opening 6, to provide a trough containing matches 22, whereby the latter can be conveniently removed when desired.

The protuberances 17 project upwardly from the extensions 16 so that they will

engage the rear of the front wall 5 and arrest outward movement of the extensions 16 and front piece 15.

- 5 Mounted in the top of the outer section and against the upper end of the inner section is a rectangular container 23, having its inner face lined with asbestos 24. The container is adapted to receive the burnt match sticks 25, and has an opening 26, 10 which registers with the opening 7. A suspension means is adapted to extend through the registering openings for supporting the receptacle when the latter is employed as a match safe.
- 15 The container snugly fits the inner face of the outer section and acts as a means for holding the inner section from shifting when the receptacle is used as a match box for shipping and storage purposes.
- 20 The outer section has a roughened surface 26^a for the striking of the matches.

What I claim is:—

1. A receptacle for the purpose set forth comprising an outer and an inner section, 25 the latter of less length than the former and in the form of a tray, said outer section having the lower portion of its front provided with an opening, a trough forming member hinged to the bottom of said inner 30 section and normally secured within said outer section and capable when released to swing through said opening to provide a trough, said member having a pair of protuberances abutting against the front wall 35 of the outer section to arrest outward movement of said member, and a container mounted in the top of said outer section and against the upper end of the inner section for maintaining the latter in the former and 40 providing a receptacle for burnt match sticks.

2. A receptacle for the purpose set forth comprising an outer and an inner section, the latter of less length than the former and in 45 the form of a tray, said outer section having the lower portion of its front provided with an opening, a trough forming member hinged to the bottom of said inner section and normally secured within said outer 50 section and capable when released to swing through said opening to provide a trough, said member having a pair of protuberances abutting against the front wall of the outer section to arrest outward movement of said member, and a container mounted in the 55 top of said outer section and against the upper end of the inner section for maintaining the latter in the former and providing a receptacle for burnt match sticks, 60 said container having a lining of asbestos.

3. A receptacle for the purpose set forth comprising an outer and an inner section, the latter of less length than the former

and in the form of a tray, said outer section having the lower portion of its front 65 provided with an opening, a trough forming member hinged to the bottom of said inner section and normally secured within said outer section and capable when released to swing through said opening to provide a 70 trough, said member having a pair of protuberances abutting against the front wall of the outer section to arrest outward movement of said member, and a container mounted in the top of said outer section and 75 against the upper end of the inner section for maintaining the latter in the former and providing a receptacle for burnt match sticks, and metallic reinforcements for said protuberances.

4. A receptacle for the purpose set forth comprising an outer and an inner section, the latter of less length than the former and in the form of a tray, said outer section having the lower portion of its front provided with an opening, a trough forming member hinged to the bottom of said inner section and normally secured within said outer section and capable when released to swing through said opening to provide a 85 trough, said member having a pair of protuberances abutting against the front wall of the outer section to arrest outward movement of said member, and a container mounted in the top of said outer section and against the upper end of the inner section for maintaining the latter in the former and providing a receptacle for burnt match sticks, said container having a lining of asbestos, and metallic reinforcements for said 90 protuberances.

5. A receptacle for the purpose set forth comprising an outer and an inner section, said outer section having the lower portion of its front provided with an opening, a 105 trough forming member hinged to the bottom of said inner section and normally secured within said outer section and capable when released to swing through said opening to provide a trough, means normally maintaining said member within said inner section, said member having a pair of extensions provided with protuberances, said protuberances when said member is released capable of abutting against the front wall 110 of the outer section to arrest movement of said member, and said inner section having means to provide pockets for said extensions.

In testimony whereof I affix my signature 120 in the presence of two witnesses.

CHARLES WESLEY ROBISON.
